United States Patent Office.

JACOB J. FOUTS. OF MIDDLETOWN, OHIO.

Letters Patent No. 77,368, dated April 28, 1868.

IMPROVED MACHINE FOR SLAUGHTERING HOGS.

The Schedule referred to in these Letters Patent and making part of the same.

TO ALL WHOM IT MAY CONCERN:

Be it known that I, JACOB J. FOUTS, of Middletown, in Butler county, in the State of Ohio, have invented a new and useful Improvement in Machines for Slaughtering Hogs; and I do hereby declare that the following is a full and exact description thereof, reference being had to the accompanying drawings, and to the letters of reference marked thereon.

The drawing represents a perspective view of my invention.

The object of my invention is to furnish a cheap and convenient structure for slaughtering hogs, by which they may be easily handled for all the purposes of dressing and hanging, as hereinafter fully described.

A B denote a rectangular frame, the top rails, C, of which extend beyond the posts, and are connected together by the short tie D. The pulley supporter E is framed into the tie D, and projects over and rests upon the cross-piece F, and is suitably slotted to receive the pulley p. To the rear end of the frame, a windlass, H, is connected, as represented in the drawings. The windlass is provided with the ratchet-wheel and pawl e d, and has the rope e connected with it at one end, and thence it passes over the pulleys o and p. An adjustable platform, I, is pivoted to the front legs or posts of the frame, the outer end of which may rest upon the edge of the scalding-box or tub, and may be adjusted to any suitable inclination for convenient use.

When in use, the outer end of platform I will be placed over the edge of the scalding-tub, and the hog to be dressed will be drawn, by means of the windlass, upon the platform, the hook g in the end of the rope being used for the purpose. When the animal is thus raised upon the platform, (the latter being placed at a suitable inclination,) the operation of sliding the hog into the vat or tub will be done with ease, and by the aid of the windlass it may be drawn upon the platform.

After cleaning the animal, the windlass will be again brought into use to elevate the hog, and bring its hind legs up between the two rails C, when the gambrel S will be inserted, in the usual manner, and then the gambrel, with the hog suspended thereon, will be pushed to the rear of the frame A B, out of the way of the workman, and to make room for others. The gambrel will slide smoothly along the top side of the upper rails C.

By the use of my machine all heavy lifting is avoided, and two persons will be enabled to perform double the amount of work that otherwise they could accomplish.

Having fully described my invention, what I claim, and desire to secure by Letters Patent, is—

The construction, combination, and arrangement of the frame A B, extended rails C, pulley-supporter E, with the adjustable platform I and windlass H, in the manner and for the purpose described.

In testimony whereof, I have hereunto set my hand, this 29th day of February, 1868.

JACOB J. FOUTS.
